MODULATION OF HIGH-FREQUENCY ENERGY

Filed Sept. 10, 1949

UNITED STATES PATENT OFFICE

2,580,970

MODULATION OF HIGH-FREQUENCY ENERGY

John J. Stickler, Ithaca, N. Y., assignor to Radio Corporation of America, a corporation of Delaware

Application September 10, 1949, Serial No. 115,051

11 Claims. (Cl. 250—17)

1

This invention relates to the modulation of ultra high frequency electromagnetic energy.

One of the more serious problems encountered in the modulation of ultra high frequency energy is the variation in impedance which is presented to the generator of the high frequency energy. This variation of impedance causes various difficulties, for example, if the high frequency generator is a magnetron the modulation becomes seriously non-linear. In general, it is desirable in the modulation of energy from ultra high frequency generators to maintain constant the impedance into which the generator works, thereby reducing standing wave losses and avoiding other difficulties.

It is an object of the present invention to provide a modulator of high frequency energy which affords a substantially constant output impedance for the generator.

It is another object of the invention to provide a novel means of modulating ultra high frequency energy.

A further object of the invention is to provide a novel ultra high frequency modulator of the absorption type.

These and other objects, advantages, and novel features of the invention will be more apparent from the following description when taken in connection with the accompanying drawing in which like reference numerals refer to like parts and in which:

Figure 1 is a partially schematically circuit diagram of one embodiment of the invention in which a single cavity resonator is employed;

Figure 1a is a cross-sectional view of another cavity resonator which may be employed in place of the resonator of Figure 1;

Figure 2 is a cavity resonator system employing two cavity resonators which may be used in the system of Figure 1; and

Figure 3 is a partially schematically circuit diagram of another embodiment of the invention in which two cavity resonators are coupled by an electron beam.

In accordance with the invention, I provide a system in which the energy from the generator is coupled through a particularly desirable network arrangement, to a cavity resonator system, the energy preferably exciting the resonator system in two independent modes both in time and phase quadrature. An electron beam absorbs energy from the resonator. In a preferred embodiment the remainder of the energy which is not absorbed by the beam is transmitted, the modulation being secured by variation of the electron

2

beam absorption. In another embodiment of the invention the energy absorbed by the beam is released to excite a second cavity resonator from which the energy is abstracted to be transmitted. Again, the modulation is secured by variation of the electron beam absorption.

Referring now more particularly to Figure 1, the energy from generator 10 is coupled to a coaxial transmission line 12. Transmission line 12 10 is connected to a diplexer network 14 which may be the same as the network disclosed and illustrated in the patent to G. H. Brown (2,454,907) issued November 30, 1948, and entitled "Radio Frequency Network." A two-wire diplexer network is disclosed in the RCA Review for June 1949, volume X, No. 2 in the article by O. M. Woodward, Jr. entitled "Reversible-beam antenna for twelve-channel television reception." The network comprises in addition to the line 12 leading into the network, an outer sleeve 16, a second coaxial transmission line 18 the outer conductor of which is connected to the sleeve 16 and the inner conductor of which is connected to the outer conductor of an extension 20 of line 12. At its 20 termination, the extension of line 12 has a slotted portion 22 the slot of which is electrically a quarter wavelength long. The inner conductor of transmission line 12 is connected to the terminal end of one side of the slotted portion. The inner conductor of line 18 is connected at the point 24 to the outer conductor of line 12 inside of sleeve 16. A pair of transmission lines 26 and 28 have their outer conductors connected to the sleeve 16 and their inner conductors connected at the terminations of the slotted portions of the outer conductor of line 12. Diplexers are known for hollow pipe waveguide transmission lines if these should be preferred.

A cavity resonator 30 is provided, which, in the present example, is rectangular having planar metallic walls which are normal to mutually perpendicular axes X, Y, and Z and therefore having also edges parallel to the said axis. In this cavity resonator 30, a cross section normal to the Y axis and parallel to the X—Z plane, is square. The lines 26 and 28 are coupled respectively through adjacent sides 32 and 34 which are normal respectively to the X and Z axes at corresponding mid-points of the side walls 32, 34. 45 Thus the lines 26 and 28 are coupled symmetrically into the resonator and are preferably so coupled that they excite two of the fundamental modes of resonance which are substantially independent of each other. That such two modes exist which are independent except for coupling

due to variations from the geometrical symmetry of construction and that due to the resistance effect of the walls is well known. Independent coupling to two such modes in a cavity resonator is described, for example, in the patent to Philip S. Carter (2,337,184) issued December 21, 1943, and entitled "Coupling Circuit." One of the lines 26, 28 is a quarter wavelength longer than the other line as measured from the end of the slotted portion 22 of the extension of transmission line 12. More generally, the terminal couplings to corresponding points 36, 38 in the resonator are in phase quadrature with respect to each other. Means are provided to produce an electron beam which is initially directed along a central line through the cavity resonator 30 in the direction of the Y axis. Such a means may comprise an electron gun structure 40 including a cathode 42, and a control grid 44 for varying the intensity of the beam. Various refinements are known for producing a well collimated beam of electrons by such means and therefore the means are only schematically disclosed. These means may further include an envelope 46 which extends entirely through apertures 49 and 51 the respective sides 50 and 52 which are normal to the Y axis. I prefer to couple the points of coupling 36 and 38 so that the output impedance of the lines 26, 28 is substantially identical and this is easily accomplished by coupling at the center point of each side. The cavity resonator 30 may be square, or its length in the direction of the Y axis may be less than that on the X and Z axes. It is preferred to excite by the couplings 36 and 38 the dominant modes which have electric vectors respectively in the Z and X directions. An anode 53 is provided within the envelope 46 to collect the beam of electrons and suitable voltage supplies are provided of which only the B+ and B- are indicated, it being understood that a bias supply may be required for the control grid 44 or other grids. The control grid 44 may be connected to a source 138 of modulating signal, as schematically indicated, to control the electron flow.

Turning now to the operation of the device, energy supplied by the generator 10 passes through the transmission line 12 to the diplexer network 14. All of such energy passes through the lines 26 and 28, and with proper design of the diplexer is divided equally therebetween in phase opposition. This is because the quarter wave slotted portion 22 effectively presents a high impedance to current flow down the sleeved portion, and therefore the two points at which the inner conductors of lines 26 and 28 are attached are at a high radio frequency potential with respect to each other. Upon reaching coupling points 36 and 38 the energy excites two dominant modes of resonance of the same frequency. Both of these modes have electric vectors normal to the direction of travel of the electron beam, and in both phase and space quadrature, resulting in circular polarization. These relations are preferable because equal absorption by the beam from each field results. A magnetic field (the means for providing which are indicated as poles of a magnet marked N, S respectively) is oriented with the magnetic lines of force parallel to the initial direction of travel of the electrons from the gun structure 40, that is, parallel to the Y axis. The electron beam interacts with the fields in the cavity resonator to absorb energy therefrom, each electron being thereby given a spiral path terminating on anode 53 with an increased

total velocity. It is apparent that a portion of the energy, however, will not be absorbed by the electron beam. The greater the number of electrons, the greater the absorption and if no electrons, there will be no absorption. The energy which is not absorbed by the beam by the respective modes will be reflected from the points of coupling. The changes in resonator impedance as presented to lines 26, 28 respectively are equal, as the beam absorbs equally from each mode, as mentioned above. Since the modes are not coupled, substantially all of the energy excited and unabsorbed by the beam, for example, at coupling point 36, will be reflected into line 26 at point 36. At point 38, similarly, the unabsorbed energy from the mode there excited will be reflected into line 28. The phases of the reflected energies, because of symmetry considerations, and because of the phase quadrature relations at points 36, 38 will necessarily be in phase quadrature. This energy now returns down the lines 26, 28 and arrives at the diplexer 14 in phase. It will be obvious to those skilled in the art that at the central operating frequency, such energy will now travel out the transmission line 18 to the antenna 60 which is here schematically represented as a simple type of dipole radiator. This because the slotted portion at the end of which the center conductor of line 12 connects is at the same radio frequency voltage for in-phase energy as the other side of the slot. Therefore, no difference in voltages in the two members of the line 12 is caused by such energy. Accordingly, substantially none of the energy is returned to the generator 10. The operation described is equivalent to saying that, if the diplexer 14 is properly matched to the transmission line 12, and the transmission line 12 is properly matched to the generator 10 there will be no reflections or standing waves on the transmission line 12 and that the generator 10 will be working into a constant and perfectly matched impedance, regardless of the amount of energy absorption. The energy absorbed by the electron beam is, of course, dissipated as heat on the anode 53.

It will be clear that other types of cavity resonators could be employed which have modes of resonance in which the electric vectors are normal to each other and in which the two inputs from lines 26, 28 would terminate in equal impedances. For example, referring to Figure 1a, a cavity resonator 30' having a circular cross section in which the points of coupling are displaced 90° from the axis at points A and B may be employed. In this case, the dominant modes are preferably excited, the two modes respectively having electric vectors as illustrated by the broken and full lines. Such modes are independent and have the same frequency of resonance.

With respect to the magnetic field oriented along the Y axis, the field strength thereof should correspond to the cyclotron frequency. The cyclotron frequency for a magnetic field strength H is defined herein as being related to H by the formula:

$$f = \frac{1}{2\pi} \frac{|e|}{m} H$$

where

$$\frac{|e|}{m}$$

is the absolute value of the ratio of the charge to mass of an electron. Thus it will be apparent that the period of rotation of the electrons is

equal to a period of oscillation of the electric field. There are certain very obvious modifications which might be desirable in the device of Figure 1. For example, the side 52 need not be apertured but may itself serve as the anode, as shown in Figure 2 hereinafter. Instead of the envelope 46 extending through this aperture and through the cavity resonator, the cavity resonator itself may be evacuated and the transmission lines 26, 28 dielectrically vacuum sealed respectively in known manner at their points of entry or coupling 36, 38 to the side walls 32, 34. The gun structure may be enclosed outside the cavity and its envelope sealed to the aperture in the wall 50, as the guns 134 and 136 in Figure 2 to their respective cavity resonators. The cavity resonator is then maintained at B+ potential so that the electrons are not accelerated during their passage through the cavity resonator except by their interaction with the fields therein. In connection with the proper strength of the magnetic field and a further explanation of absorption of energy by an electron beam, reference may be made to an article by C. L. Cuccia entitled "The electron coupler—a developmental tube for amplitude modulation and power control at ultra-high frequencies" in the RCA Review, volume X, No. 2 for June 1949, beginning at page 270.

If phase modulation is desired, it may be secured by using a different value of magnetic field strength than the cyclotron value. As well known, there is a second value of field strength which makes the cavity resonator appear purely reactive to the coupled lines rather than purely resistive. If this second value of magnetic field strength is used, the output is phase modulated with electron beam intensity variations. With either value of magnetic field strength, the change in beam intensity causes a change in impedance of the cavity resonator resulting in modulation. This second value of field strength is well known in the art, although it does not bear an appellation such as is borne by the cyclotron value as interrelated with the frequency, in accordance with the equation above, so far as applicant knows.

Referring now to Figure 2, it will be apparent that two separate cavities 130 and 132 might be utilized instead of the single cavity, and will function as equivalents thereof, provided the electron beams and magnetic field values would be the same in each case and the beams modulated in the same fashion. Such an arrangement is illustrated in Figure 2 in schematically perspective view, with the transmission lines 26, 28 leading respectively to the two cavities which have the same resonant frequency for the particular mode coupled at the termination of the lines 26, 28. Again, lines 26 and 28 differ by a quarter wavelength at the operating frequency and lead to a network as shown in Figure 1. Electron guns 134, 136 are arranged to produce a beam of electrons in each cavity together with means for providing a magnetic field parallel to the initial direction of the electron beam produced by the guns. The grids of the electron guns 134, 136 may be tied together to receive a modulating signal from a common source 138.

Figure 3 shows a quite different modification of the invention comprising a generator 10, a transmission line 12 coupled thereto as before, a network 14 which may be the same as the network 14 of Figure 1, a pair of transmission lines 26, 28 coupled to the network as before, 70

and a transmission line 18 coupled to the network 14 as before and terminated in a resistor R1. Two cavity resonators 230 and 232 are provided having a common wall 234 in which is a communicating aperture 236 of small diameter. An electron beam illustrated by a dotted line 238 couples the two cavities by being injected at the wall 240 of rectangular cavity resonator 230 and being directed to pass through the aperture 236 toward the far wall 242 of rectangular cavity resonator 232, the wall 242 serving as an anode for the beam. The beam may be modulated in intensity by a suitable grid (not shown in this figure). As before, the lines 26 and 28 are coupled at points 244 and 246 respectively by cavity resonator 230 to excite modes which have the same frequency of resonance and which also have electric vectors normal to the axis of the electron beam 238. Cavity resonators 230 and 232 are similar and it will be apparent that the energy absorbed by the electron beam 238 is coupled to two similar modes in cavity resonator 232. Thus the energy absorbed in cavity resonator 230 is coupled to cavity resonator 232 to excite two similar modes therein. The energy is picked up by two transmission lines 248 and 250 at points 252 and 254 respectively and which are coupled as before to two independent modes having the same frequency of resonance as the modes in resonator 230 and the same frequency of resonance as each other. Transmission lines 248 and 250 are coupled to the diplexing network 256 which is similar to the network 14 and coupled to two further transmission lines 258 and 260, the latter of which leads to an antenna 262 and the other of which is terminated in a matched absorbing resistor R2.

In operation, the generator 10 works into the transmission line 12 to couple energy in phase opposition to the transmission lines 26 and 28. Due to the quarter wavelength difference in the lengths of lines 26 and 28, the energy is coupled into the cavity resonator 230 and absorbed by the electron beam 238 which in turn couples the energy to the modes in cavity resonator 232 where it is picked up by lines 248 and 250. Depending on which of the lines 248 and 250 is longer, the energy arrives at diplexer 256 either in phase or in phase opposition. Assuming in this case that it arrives in phase, it will be transmitted through transmission line 260 to antenna 262. Any out of phase components, that is, components arriving in phase opposition will be absorbed by the absorbing resistor R2. As before, generator 10 works into a fixed impedance. It will also be apparent that transmission line 260 and antenna 262 see a constant impedance.

It will be obvious to those skilled in the art that in Figure 1 generator 10 may be connected to transmission line 18 and antenna 60 to transmission line 12, and the operation of the device in that event will also be obvious to those skilled in the art from what has been said heretofore.

What I claim is:

1. A circuit comprising first and second pairs of transmission lines, a network therebetween coupling at the center operating frequency the first of said first pair of lines to said second pair of lines in phase opposition at the points of connection of said second pair to said network and coupling the second of said first pair of lines to said second pair of lines in phase at said points, a resonator system having two independent resonant modes of oscillation at said frequency, each of said second pair of lines being coupled to said

resonator system means coupled to said resonator system to effect respectively said modes to change equally the impedance as presented to each of said second pair of lines by said resonator system, each line of said second pair being coupled to affect respectively one and not to affect the other of said modes and one of said second pair of lines being a quarter wavelength longer from its said point of network connection to its effective point of coupling to said resonator system than the other, whereby energy applied to the circuit through one line of said first pair is transmitted to said second line of said first pair in an amount depending on the changes in said impedances presented to said lines.

2. A circuit comprising first and second pairs of transmission lines, a network therebetween coupling at the center operating frequency the first of said first pair of lines to said second pair of lines in phase opposition at the points of connection of said second pair to said network and coupling the second of said first pair of lines to said second pair of lines in phase at said points, a resonator system comprising a cavity resonator having two independent resonant modes of oscillation at said frequency the electric vectors of which are normal to each other, means coupled to said resonator system to affect respectively said modes to absorb equally energy therefrom and comprising an electron beam having its axis normal to said vectors and a magnetic field, said magnetic field being substantially uniform throughout the electron travel through the cavity resonator, each line of said second pair being coupled to said resonator system to affect respectively one and not to affect the other of said modes and one of said second pair of lines being a quarter wavelength longer from its said point of network connection to its effective point of coupling to said resonator system than the other, whereby energy applied to the circuit through said first line of said first pair is transmitted to said second line of said first pair in an amount depending on the impedance presented to said lines by said resonator system.

3. The circuit claimed in claim 2, the strength of said magnetic field being substantially equal to the cyclotron value whereby said impedance is substantially purely resistive.

4. The circuit claimed in claim 2, the strength of said magnetic field being substantially equal to the value required to make said impedance substantially purely reactive.

5. The circuit claimed in claim 2, further comprising a generator coupled to one of said first pair of lines, and an antenna coupled to the other of said first pair of lines.

6. A circuit comprising first and second pairs of transmission lines, a network therebetween coupling at the center operating frequency the first of said first pair of lines to said second pair of lines in phase opposition at the points of connection of said second pair to said network and coupling the second of said first pair of lines to said second pair of lines in phase at said points, a resonator system comprising a first cavity resonator having two independent resonant modes of oscillation at said frequency and a second cavity

resonator similar to said first and having two similar independent resonant modes of oscillation at said frequency, energy coupling means comprising an electron beam directed through said first resonator and thence through said second resonator and a means to provide a substantially uniform magnetic field axially of said beam and having the cyclotron value for said frequency throughout the travel of said beam through said resonators, said beam being coupled to said first cavity modes to absorb equally energy therefrom and being coupled to said second cavity modes to impart energy thereto, each line of said second pair of lines being coupled to one and not to the other of said first cavity resonator modes and one of said second pair of lines being a quarter wavelength longer from its said point of network connection to its effective point of coupling to its respective mode than the other, third and fourth pairs of transmission lines, a second network therebetween coupling at the center operating frequency the first of said third pair of lines to said fourth pair of lines in phase opposition at the points of connection of said fourth pair to said second network and coupling the second of said third pair of lines to said fourth pair of lines in phase at said points of connection of said fourth pair, each line of said fourth pair being coupled to one and not to the other of said modes of said second resonator and one of said fourth pair of lines being a quarter wavelength longer from its said point of second network connection to its effective point of coupling to its respective mode than the other, whereby energy applied to the circuit through one line of said first pair is transmitted to one line of said fourth pair in an amount depending on the absorption thereof by said beam in said first cavity resonator.

40 7. The circuit claimed in claim 6, further comprising a generator coupled to one of said first pair of lines.

8. The circuit claimed in claim 2, said cavity resonator being a rectangular cavity resonator having a square cross section.

45 9. The circuit claimed in claim 2, the said resonator being a circular cavity resonator.

10. The circuit claimed in claim 1, said lines being co-axial transmission lines.

50 11. The circuit claimed in claim 1, said resonator system comprising two separate and similar cavity resonators.
